UNITED STATES PATENT OFFICE

2,255,337

COIN SLIDE

Joseph W. Srodulski, Chicago, Ill.

Application September 29, 1939, Serial No. 297,050

3 Claims. (Cl. 194—1)

This invention relates to improvements in control mechanism for use in vending machines and has as its principal object the provision of a simplified operating slide structure which is freed for effective movement to operate the vending machine by utilizing a tested coin to release a latch for the slide.

Another object of the invention is to simplify the construction of a coin slide by providing an improved guide means therefor which dispenses with the expensive die cast sleeve structures heretofore employed in such devices.

Another object is the provision of a full stroke mechanism arranged to guide the slide and to provide a reinforced ratchet for cooperation with a full stroke dog.

Another object is the provision of a slide having guiding ribs along a portion of its length working in slots in a stationary mounting member near one end of the slide, a gliding shoe at 20 the opposite end of the slide, and full stroke mechanism including a combined ratchet and guide bar coating with a full stroke dog and providing a guiding rib on the opposite side of the slide from the first-mentioned ribs.

Yet another object is the provision of a coin slide having a slot into which a tested coin fits to project through the slide normally to the plane thereof and a latch for the slide provided with a cam edge against which the coin is borne to 30 cam the latch into released position.

Other objects, advantages and novel aspects of the invention reside in the various details of construction as well as the arrangement and mode of operation of the parts of the preferred embodiment described hereinafter in view of the annexed drawing, in which:

Fig. 1 is a vertical transverse section through the control unit;

Fig. 2 is a longitudinal vertical section along line 2—2 of Fig. 1;

Fig. 3 is a horizontal section looking up from above the slide in the direction of line 3—3 of Fig. 2; while

Fig. 4 is a perspective of the slide, latch and dogging mechanism.

Referring to Fig. 2, the improved control mechanism includes an elongated control slide 10 having a handle portion at its front end 11 and provided on its under side with a plurality of guiding ribs 12 (Fig. 1 also) spaced apart across the slide and extending in the length thereof about two-thirds the distance to the opposite or rear end of the slide proper.

At its inner end, the slide is provided with a shoe 13 (Fig. 4 also) secured to the under side thereof by screws 14 and having its under side recessed as at 15 so as to provide runner surfaces 16 to facilitate the gliding movement of the slide at its rear end, the runner surfaces resting upon

5 a horizontal supporting member 17 constituting a part of a housing structure including a front wall portion 18 in which there are spaced grooves to receive the several ribs 12 which effectively guide the slide at its front end.

Means for guiding the slide at its inner or rear end and also providing parts for cooperation with a full stroke dog mechanism, includes the provision (Fig. 4) of an angle bracket having one side flange 19 mounted by means of the screws 14 flush against the upper side of the slide with a serrated edge portion 21 extending in parallelism with one long edge of the slide. The other flange portion 22 of the angle bracket projects upwardly and normally from the plane of the slide for sliding movement in a groove 23 (Fig. 1) formed on the under side of a casting 24 which provides a cover plate for the slide and also a vertical chute section for guiding tested coins into operative engagement with the slide.

The cover casting is secured to the horizontal riding plate 17 by means such as the screws 19 threading into suitable bosses in the casting. Thus, the movement of the vertical or projecting flange portion 22 of the dog ratchet 20, in the groove 23, cooperates with the movement of the ribs 12 in the slots of the front wall of the housing to guide the slide accurately in its reciprocable movement. This is a simplified construction which greatly reduces the cost of manufacture of this class of slide because heretofore, expensive die castings have been required in providing a sleeve in which the slide could move.

A full stroke dog 26 (Fig. 4) is pivoted on a pin 27 which extends into a large boss 28 (Figs. 1 and 3) cast integrally with the cover member on the inner side thereof and of a size adequate to provide an unusually sturdy mounting for the dog, the boss 28 in fact being joined by a web portion 29 with the side wall of the casting and including a tapped portion to receive one of the mounting screws 19 for the cover plate.

The dog has a nose portion 28a which is normally positioned by action of a spring 30 to engage or ride in teeth of the serrated ratchet edge 21 to prevent inward movement (toward the right, Figs. 2 and 4) of the slide after the same has been pulled outwardly (toward the left) far enough so that the first ratchet tooth 21a engages with the dog, it being necessary to pull the slide out the entire distance in order that the rear end 21b of the ratchet be moved past the dog to permit the latter to be swung in the opposite direction so as to idle ineffectively over the ratchet teeth when the slide is pushed inwardly again.

The guiding flange 22 on the ratchet is of adequate strength to prevent the inner end of the slide from swinging out of engagement with the dog when a blow is struck against the handle in

an attempt to release the dog, and the mounting boss 28 is similarly constructed to provide a firm mounting for the dog.

Means actuated by a coin cooperably with the slide to release the slide for full stroke movement, includes the provision of a cam latch 35 (Fig. 4) pivotally mounted on the boss 36 on the under side of the cover casting, and having a cammed nose portion 37 arranged in advance of a coin slot 38 through the slide. The cam latch has a depending lug 39 which projects into a longitudinally elongated slot 40 in the edge of the slide, the lug latching the slide against effective movement by permitting a limited amount of idle or free-play longitudinal displacement of the slide in order to effect release of the latch means. Spring means 41 on the pivot boss of the cam latch urges the latter into a normal position inwardly of the slide so as to position the locking lug 39 in the slot in the edge of the slide. A depending boss 35a (Fig. 1) is disposed just above the cam portion of the latch to prevent prying the latter away from the slide. A depending lug 42 on the cam latch engages the edge of the slide to limit the inward movement by the spring.

In the operation of the device, the coin is received from a suitable testing apparatus (not shown) and guided by the chute section 25 into position to drop into the coin slot 38 when the slide is disposed inwardly, the coin dropping partly through the slot to rest on the floor portion 17 in the region behind (to the right, Fig. 2) a drop-out opening 17a.

With the coin positioned as aforesaid in the slot 38, the handle 11 is grasped and pulled forward (left, Figs. 2 and 4) and because of the length of the slot 40 the forward edge of the coin is brought to bear against the cam edge 37 of the latch lever, and as the slide continues to move outwardly the latch lever 35 is cammed to withdraw the lug 39 from the notch in the edge of the slide so that the latter is free to move into fully retracted position, such movement carrying the coin in the pocket 38 along the floor portion 17 and into the drop-out opening 17a from which the coin moves into a suitable receptacle. Meanwhile, the dog 26, coacting with the ratchet means in the manner heretofore described, makes it necessary to draw the slide out its entire length before the same can be restored. This is to prevent partial movements of the slide which would permit effective operation thereof a number of times using the same coin. The arrangement is such in the illustrative embodiment that a stack of vendible articles (not shown), such as candy bars, is disposed above the rear end of the slide and the shoe 13, so that when the slide is retracted or pulled out, the bottommost article drops onto the floor 17 in front of the end of the retracted shoe, and when the slide is pushed in, the rear end of the shoe bears against the candy bar or other article and pushes the same into a discharge chute (not shown).

It will be apparent from the foregoing description that the rib means 12 and the guiding flange 22 in the arrangement described are the principal means for guiding the slide in its operative movement; and it will also be apparent that the combination guide and ratchet means 21-22 is advantageous not only because of its simplicity 70 but also in view of the fact that any stress ex-

erted upon the ratchet in a fraudulent attempt to force the slide, is taken up largely in the flange portion 22 and the guiding track 23 therefor and not in the slide itself, as is the case with the old type of construction where the ratchet was formed in the edge of the slide. Moreover, the slide may be cast and any number of ribs 12 provided therein to make the same as strong as necessary. The simplicity and effectiveness of the latch means 35 is a further advantage.

The various advantages and objects of the invention may be accomplished by modifications of the particular embodiment specifically described herein, and it is intended that the appended claims shall include all equivalent arrangements fairly coming within their call.

Having thus described my invention, what I claim as new and desire to protect by Letters Patent is:

1. In a coin slide, a combination guide and full stroke ratchet in the form of an angle bracket attached with one flange flush against a side of the slide and said flange having a serrated ratchet edge in the direction of the length of the slide close to an edge thereof, said angle bracket having its other flange projected normally from the plane of the slide, and engaged in guiding means extending longitudinally of the slide, said ratchet edge of the bracket being adapted for cooperation with a full stroke dog.

2. In a control mechanism for vending machines, an operating slide and full stroke means therefor including an angle bracket mounted with the surface of one flange thereof flush against a side of the slide, said bracket having an adjoining flange projecting out of the plane of the slide at right angles thereto, stationary means providing a guide groove into which said projecting flange of the bracket fits, the flange portion of the bracket which is flush with the slide having an edge with ratchet teeth therein disposed closely parallel with a long edge of the slide, and a full stroke dog mounted at one side of the slide opposite said ratchet teeth and arranged for cooperation with the latter to permit the slide to move from an initial position in one direction and prevent movement of the slide in an opposite direction unless the slide has been moved a certain distance from initial position.

3. In a coin control, the combination with a reciprocable slide of dog controlled means comprising an angled member attached to one side of the slide with an edge portion disposed close to a long edge of the slide and provided with toothed formations for cooperation with a dog, said angled member having a projection extending out of the plane of the slide to fit into a guiding groove, stationary means providing a guiding groove into which said projecting portion fits, and a dog cooperable with said toothed formations to permit movement of the slide in one direction from an initial position and prevent movement of the slide in an opposite direction until the same has been moved a predetermined distance from initial position, any stress due to forcing the slide before the same has been moved said predetermined distance being taken up largely in said angled member and said groove means.

JOSEPH W. SRODULSKI.
